UNITED STATES PATENT OFFICE

FREDERICK S. BITGOOD, OF SAN FRANCISCO, CALIFORNIA

PORTABLE FUEL-BURNER CONSTRUCTION

Application filed October 5, 1927. Serial No. 224,133.

My invention relates to improvements in fuel burner construction wherein a plurality of burner units are detachably mounted and made separately removable from a fabricated portable mounting box.

The primary object of my invention is to provide an improved construction and arrangement for fuel burners.

Another object is to provide an improved construction wherein vertically disposed burner tubes are arranged in burner units arranged to be independently mounted and separately removed from a mounting.

A further object is to provide an improved burner construction comprising a plurality of separate burner units each consisting of an integral structure, forming fuel manifold, burner tube and nozzle mounting, induction tube supports, and unit supports, to facilitate construction and assembly and permit the ready removal of any particular unit independently of the remaining units.

Another object is to provide an improved burner for vertical firing whereby separate units may be independently removed without shutting down the remaining burners and without interrupting the operation of the burner.

A further object is to provide an improved means for mounting burner units within a mounting box to facilitate the placing and removing of burner units.

A still further object is to provide an improved burner construction which is entirely self contained and which is readily transportable.

I accomplish these and other objects by means of the improved device disclosed in the drawings forming a part of the present application wherein like characters of reference are used to designate similar parts throughout the specification and drawings and in which,

Fig. 1 is a broken plan view of my improved burner construction;

Fig. 2 is a longitudinal vertical section of the burner;

Fig. 3 is a front elevation of the burner construction, partly broken away and shown in transverse section;

Fig. 4 is a broken side elevation of one of my improved burner units showing the manner in which said unit is detachably mounted; and

Fig. 5 is a front elevation of the burner unit and unit mounting means.

Referring to the drawings, the numeral 1 is used to designate in general a mounting box consisting of a frame fabricated from structural angle iron, to form corner posts 2 connected at their tops by upper beams 3 extending across the sides, and beams 4 extending across the front and back of the box. The posts 2 and the beams 3 and 4 are formed from angle iron sections arranged in abutting relation as shown in the drawings. Bottom angle iron sections 6 and 7 are connected between the bottoms of the posts 2 across the sides and across the front and back respectively.

A bottom plate 8 formed from suitable sheet metal is secured across the bottom of the frame, and plates 9 are secured upon the sides of the frame. A damper frame 11 is hingedly mounted within the front of the frame 1 and upon said frame 11 is pivotally mounted a damper plate 12 supported upon a damper shaft 13 engaged by notches 14 formed in outwardly extending flanges 16. The damper plate extends substantially across the front of the box and is tiltable upon the shaft 13 to provide a desired degree of opening to admit air to the burner box.

The back of the box 1 is provided with an upper door portion 17 hingedly connected to the top portion of the box frame, and a lower door portion 18 hingedly connected to the lower angle member 7. The door portions 17 and 18 have their adjacent edges arranged to meet in substantially abutting relation, and matching recesses 19 are formed in said edges for a purpose hereinafter more fully explained.

A plurality of burner units are detachably mounted within the mounting box 1, each unit consisting of a fuel manifold 21 having a plurality of induction tube supports 22 formed integrally therewith and supported above the manifold by webs 23 cast integrally with the manifold and supports. The supports 22 are provided with upwardly dis-

posed annular seats arranged to receive the lower edges of induction tubes 24 formed from suitable refractory material such as in common usage. Burner tubes 26 are connected into the manifold 21 in axial alinement with the tube supports 22, said burner tubes 26 extending upwardly through the supports 22 and into the induction tubes 24. Nozzles 27 are mounted upon the upper ends of the burner tubes 26 through which fuel is delivered upwardly for combustion. A supporting arm 28 is formed upon one end of the manifold 21. The opposite end of the manifold 21 is connected to a fuel supply connection 29, arranged to extend outwardly through the back of the box 1 through the matching recesses formed in the edges of the doors 17 and 18.

The burner units are removably supported within the box 1 by means of brackets secured within the front and back of the box 1, each bracket consisting of a pair of arms 31 secured at their upper ends upon the beams 4 and extending downwardly in spaced parallel relation. Each pair of bracket arms 31 at the front of the box 1 is arranged to receive the end of a supporting arm 28 of a burner unit, and the corresponding pair of bracket arms 31 at the back of the box is arranged to receive the supply connection 29 of the unit, said unit being moved upwardly into engagement with the spaced ends of the arms 31. Retaining pins 32 are arranged to be inserted into engagement with notches 33 formed in the tops of laterally extending lugs 34 formed upon the bottoms of the arms 31, said pins spanning the space between the arms and supporting the ends of the units between said arms. A pin 35 is secured between the arms 31 of each front bracket to give rigidity and to limit the upward movement of the connection 29 therebetween. A split cotter pin 36 is inserted through the arms 31 of each back bracket to retain the arm 28.

Fuel is supplied to the burner units through a main supply manifold 37 mounted across the back of the box 1 and supported upon bracket arms 38 extending rearwardly from the mounting box frame and held in position by yokes 39. The supply manifold 37 is connected to each burner unit through a suitable valve 41 connected between the manifold and the supply connections or headers 29 in any convenient manner, the supply of fuel to each burner unit being independently controlled by its valve 41. A union 42 connected into the supply connection 29 permits each union to be readily disconnected from the supply manifold 37 and its connections when desired.

A yoke 43 is pivotally connected upon the bracket arms 38 and arranged to be swung downwardly to engage the upper sides of the supply connections 29 and hold said connections rigidly against the retaining pins 32 whereby the burner units may be held

rigidly in position when the burner is being transported. The yoke 43 is arranged to be swung rearwardly as indicated in dotted lines in Fig. 4 to disengage the connections 29 and permit the ready removal of the units 76

The burner units may be constructed with any desired number of burner tubes 26 and induction tube supports 22, and any desired number of units may be installed to obtain burner constructions of a desired size. In the drawings I have illustrated a form wherein six units are provided, each unit being provided with eight burner tubes and induction tube supports. The units extend horizontally across the box 1, from front to back, and are arranged in close proximity to each other whereby a bank of forty-eight regularly spaced individual burner tubes and nozzles is obtained. 75 80 85

In operation, the mounting box 1 is fabricated as a unit, designed for any desired form of service. The mounting box with its burner units is entirely self contained whereby it may be readily transported as a whole for installation in connection with a boiler, retort, or other device, not shown, and if desired, shifted from one service to another. In installing the burner, the box 1 is set in position as desired. The fire box and furnace body 43 is then constructed over the box in any desired manner. When in service, the fuel supply to any particular burner unit may be shut off and the unit disconnected from the supply manifold connections. A 90 95 100 simple removal of the pins 32 then permits the entire burner unit, with its burner tubes and induction tubes, to be removed from the mounting box for individual repair or replacement without interrupting the operation of the remaining burner units and without requiring that the burner be shut down. This is of particular value and importance as a continuous operating, vertically fired burner, such as required in numerous types of boiler and retort installations, is obtained. 105 110

While I have illustrated and described only the preferred construction and arrangement, the details of the structure may of course be modified in numerous ways without departing from the spirit of my invention. I therefore do not wish to restrict myself to the specific form and construction illustrated and described, but desire to avail myself of all modifications which may fall within the scope of the appended claims. 115 120

Having thus described my invention what I claim as new and desire to secure by Letters Patent is:

1. A portable fuel burner construction 125 comprising a mounting box; a plurality of burner units; supporting brackets secured within the front and back of the box to receive the ends of the units; detachable retaining means removably engaging the 130

brackets to normally secure the units upon the brackets; a plurality of vertically disposed fuel burning nozzles connected into each unit; and means for delivering fuel to the burner units.

5 2. A portable fuel burner construction comprising a mounting box; a plurality of burner units; supporting brackets comprising pairs of downwardly extending arms secured within the front and back of the box, each pair of arms being arranged to receive one end of a burner unit therebetween; retaining means detachably engaging the arms and arranged to extend between the arms of each pair to separately support the burner units; and means for delivering fuel to the burner units.

10 20 3. A portable fuel burner construction comprising a mounting box; a plurality of burner units; supporting brackets comprising pairs of downwardly extending arms secured within the front and back of the box, each pair of arms being spaced at the bottom to receive one end of a burner unit moved upwardly therebetween; retaining means detachably engaging each pair of arms and spanning the space between the arms below the ends of the units for removably supporting said units; and means for delivering fuel to the burner units.

25 30 4. A portable fuel burner construction comprising a mounting box; a plurality of burner units; supporting brackets comprising pairs of downwardly extending arms secured within the front and back of the box, each pair of arms being spaced at the bottom to receive one end of a burner unit moved upwardly therebetween; lugs formed upon the arms; retaining pins detachably engaging the lugs of each pair of arms and spanning the space between said arms for removably supporting said units; and means for delivering fuel to the burner units.

45 50 5. A portable fuel burner construction comprising a mounting box consisting of a frame formed from abutting angle iron sections; plates secured across the sides and bottom of the frame; doors hingedly mounted upon the box to close the front and back of the box; and a plurality of burner units detachably mounted within the box and separately removable therefrom; and means for securing the burner units against displacement when the box is being transported.

6. A portable fuel burner construction comprising a mounting box consisting of a frame formed from abutting angle iron sections; plates secured across the sides and bottom of the frame; doors hingedly mounted upon the box to close the front and back of the box; and a plurality of burner units detachably mounted within the box; and a securing member pivotally mounted upon the frame and movable to engage the burner units

to secure the same when the box is being transported.

7. A portable fuel burner construction comprising a mounting box consisting of a frame formed from abutting angle iron sections; plates secured across the sides and bottom of the frame; doors hingedly mounted upon the box to close the front and back thereof; brackets mounted within the front and back of the box; a plurality of burner units mounted upon the brackets; and means for detachably securing the units upon the brackets.

8. A portable fuel burner construction comprising a mounting box fabricated from structural iron framing and provided with sheet metal sides and bottom; a plurality of burner units detachably mounted in separately removable relation within the box, each unit comprising a manifold provided with a plurality of induction tube supports formed integrally therewith, and burner tubes connected into the manifold and extending upwardly through each induction tube support; and means for supplying fuel to the unit manifolds.

9. A fuel burner unit comprising a tubular manifold; a plurality of induction tube supports formed integrally with the manifold and arranged to receive refractory induction tubes; burner tubes connected into the manifold and extending through the induction tube supports, said tubes being provided with burner nozzles; and means carried by the unit whereby said unit may be detachably mounted within a mounting box.

10. A fuel burner unit comprising a tubular manifold; a plurality of induction tube supports formed integrally with the manifold and arranged to receive refractory induction tubes; burner tubes connected into the manifold and extending upwardly through the induction tube supports, said tubes being provided with burner nozzles; an extension formed upon one end of the manifold to form mounting means for the manifold; and a supply connection connected to the other end of the manifold and forming mounting means for said other end.

11. A fuel burner construction comprising a transportable mounting box fabricated from structural iron framing and sheet metal sides and bottom; a plurality of burner units, each consisting of a tubular manifold, a plurality of induction tube supports formed integrally with the manifold and arranged to receive refractory induction tubes, and burner tubes connected into the manifold and extending upwardly through the induction tube supports; a plurality of supporting brackets mounted within the front and back of the mounting box; an extension formed upon one end of each burner unit and arranged to engage a bracket; and a supply connection connected to the other end of the

manifold and arranged to engage a bracket to support said other end of the unit.

12. A fuel burner construction comprising a transportable mounting box fabricated from structural iron framing and sheet metal sides and bottom; a plurality of burner units, each consisting of a tubular manifold, a plurality of induction tube supports formed integrally with the manifold and arranged to receive refractory induction tubes, and burner tubes connected into the manifold and extending upwardly through the induction tube supports; a plurality of supporting brackets mounted within the front and back of the mounting box; an extension formed upon one end of each burner unit and arranged to engage a bracket; and a supply connection connected to the other end of the manifold and arranged to engage a bracket to support said other end of the unit; and means detachably engaging the brackets and the unit for removably securing each unit within the box independently of the other units.

In witness whereof, I hereunto set my signature.

FREDERICK S. BITGOOD.
